L. HETU

PROTECTIVE LIQUID HOLDER

Filed May 7, 1923

Inventor

Louis Hetu

By *Jolanta Polachek*

Attorney

UNITED STATES PATENT OFFICE.

LOUIS HETU, OF WOONSOCKET, RHODE ISLAND.

PROTECTIVE LIQUID HOLDER.

Application filed May 7, 1923. Serial No. 637,160.

To all whom it may concern:

Be it known that I, LOUIS HETU, a citizen of Canada, residing at Woonsocket, in the county of Providence and State of Rhode Island, have invented certain new and useful Improvements in Protective Liquid Holders, of which the following is a specification.

This invention relates to a liquid holder and applicer which may be used in connection with various liquids, being particularly useful in connection with the application of certain liquids which emit fumes which are disagreeable or injurious to the health, such as the liquid rubber cement which contains a percentage of naphtha, and which it is therefore undesirable to leave exposed.

The invention has for an object to provide a novel device which will permit of the removal of a quantity of liquid from a closed container without opening the body of the container, and which will also cause the discharged liquid to be evenly spread or distributed upon a brush which is used to apply it to the desired part.

For further comprehension of the invention, and of the objects and advantages thereof, reference will be had to the following description and accompanying drawings, and to the appended claims in which the various novel features of the invention are more particularly set forth.

Fig. 1 of the drawings is a vertical sectional view of my improved device, indicating the brush in elevation as in position to receive the liquid.

Fig. 2 is a side view of the device in inoperative position, with certain exterior parts broken away.

Fig. 3 is a horizontal sectional view taken on the line 3—3 of Fig. 1.

As here embodied my improved device comprises a cylindrical container 10 to which is attached midway between its ends a bracket 11 pivoted as indicated at 12 to a second bracket 13 fixed to a suitable support. At the discharge of the container chamber is a horizontal partition member 15 which is spaced a slight distance from the end of the cylindrical wall of the container, and is provided with a central opening surrounded by an upstanding annular flange 16, thus providing a small measuring compartment 17 in the end of the container. Upon the top of this flange considering the device in its operative position shown in Fig. 1, a valve 18 seats and is formed on the upper end of a

stem 19 on whose lower end a second valve 20 is mounted, these valves 18 and 19 being adapted to close the upper and lower ends of the measuring chamber 17 respectively; 60 while the stem 19 is of such length that both valves cannot be open at the same time, one closing just before the other opens.

Fixed to the bottom face of the valve 20 is a disk 22 having a number of perforations 23 spaced throughout the area thereof and provided at its edge with an upstanding flange 24, the top edge of this flange being accommodated in a downwardly opening recess formed by making the bottom of the 70 main container chamber of less diameter to leave a space between the edge of the partition member 15 and the cylindrical wall of the container. Located in the said recess, and bearing downwardly on the flange 24, 75 is a coiled expansion spring 26 which acts to keep the valve 18 normally closed.

The liquid discharged from the measuring compartment is adapted to be received on a brush comprising a backing 30 of such 80 diameter as to fit snugly in the projecting lower part of the container, and whose bristles 31 engage under the disk 22. Projecting upwardly from the back of the brush, and being of somewhat less length than the 85 bristles 31, are a number of pins 33 which are adapted to engage the disk to raise the latter, and with it valves 18 and 20, when the brush is to receive the measured supply of liquid.

To the wall or other support, indicated at S, on which the container is pivoted, I preferably hinge a cover 35 which may be utilized to fit over the discharge end of the container and cover the disk 22 when the device 95 is not being used.

It is believed that the manner of operation and use of my improved device will be readily understood from the foregoing description. When the brush, which is provided 100 with an ordinary handle 36, is to receive a supply of the liquid it is pressed upwardly in the lower end of the container, the pins 33 engaging the disk 22 and opening valve 18 and closing valve 19. The measuring compartment 17 then fills with liquid, after the brush is slightly lowered, spring 26 acting to close valve 18 and open valve 19. The liquid then spreads out on the disk 22 and passes through the apertures 23 in the latter 110 onto the brush, which is then removed.

The container may be reversed when de-

sired and the cover 35 engaged over its discharge end, as indicated in Fig. 2. A suitable filling opening, closed by a cap 40 may be provided in the container.

5 Having thus described my invention what I claim as new and desire to protect by Letters Patent of the United States is as follows:

1. A device of the class described comprising a container having a discharge opening at one end, an annular flange surrounding said opening and providing a measuring compartment, valves adapted to operate inversely in unison for controlling inlet and discharge ends of said measuring compartment, and a distributing element fixed to the valve controlling the discharge end of the said compartment.

2. A device of the class described comprising a container having a discharge opening at one end, an annular flange surrounding said opening and providing a measuring compartment, valves adapted to operate inversely in unison for controlling inlet and discharge ends of said measuring compartment, and a distributing element fixed to the valve controlling the discharge end of the said compartment, said distributing element being in the form of a disk having perforations spaced over the area thereof.

3. A device of the class described comprising a container having a discharge opening at one end, an annular flange surrounding said opening and providing a measuring compartment, valves adapted to operate inversely in unison for controlling inlet and discharge ends of said measuring compartment, and a distributing element fixed to the valve controlling the discharge end of the said compartment, said distributing element being in the form of a disk having perforations spaced over the area thereof, the side wall of the container being extended to enclose the said disk.

4. A device of the class described comprising a container having a discharge opening in its lower end, an annular upstanding flange surrounding said opening and forming a measuring compartment, a valve adapted to seat on the upper end of said flange to close the top of the said compartment, a second valve adapted to close the bottom of the said compartment, a stem on which said valves are fixed, and a perforate disk fixed to the second named valve.

55

ment, a second valve adapted to close the bottom of the said compartment, a stem on which said valves are fixed, and a perforate disk fixed to the second named valve.

5. A device of the class described comprising a container having a discharge opening in its lower end, an annular upstanding flange surrounding said opening and forming a measuring compartment, a valve adapted to seat on the upper end of said flange to close the top of the said compartment, a second valve adapted to close the bottom of the said compartment, a stem on which said valves are fixed, and a perforate disk fixed to the second named valve, and a spring bearing on said disk to hold the first valve normally closed.

6. A device of the class described comprising a container having a discharge opening in its lower end, an annular upstanding flange surrounding said opening and forming a measuring compartment, a valve adapted to seat on the upper end of said flange to close the top of the said compartment, a second valve adapted to close the bottom of the said compartment, a stem on which said valves are fixed, and a perforate disk fixed to the second named valve, and means pivotally mounting said container whereby it may be swung to a position with its discharge end uppermost.

7. A device of the class described comprising a container having a discharge opening in its lower end, an annular upstanding flange surrounding said opening and forming a measuring compartment, a valve adapted to seat on the upper end of said flange to close the top of the said compartment, a second valve adapted to close the bottom of the said compartment, a stem on which said valves are fixed, and a perforate disk fixed to the second named valve, and means pivotally mounting said container whereby it may be swung to a position with its discharge end uppermost, and a cover adapted to engage whichever end of the container is uppermost.

In testimony whereof I have affixed my signature.

LOUIS HETU.
